SIGN

Everett L. Register, Springfield, Ill., assignor to
Reflection Corporation of America, Springfield, Ill., a corporation of Illinois

Application September 22, 1937, Serial No. 165,017

1 Claim. (Cl. 40—125)

This invention relates to signs, and particularly to reflector or illuminated signs adapted for use, for example, along highways or the like, and wherein the illumination is produced by reflected lights from outside the sign either by daylight or artificial light, as, for example, the headlights of motor vehicles or other lights projected thereon, the present invention being an improvement on the type of sign shown and described in my co-pending application filed August 26, 1936, Serial No. 97,927.

One object of the present invention is to provide a novel construction and arrangement of elements comprising letters, numerals, symbols or other indicia constituting a sign of the character described in which letters or other indicia may be assembled in a unitary sign construction, or the individual letters may be made up in stock, and then combined in a suitable support as required to produce a finished sign.

Another object of the invention is to provide means for protecting the light reflecting material or portions thereof against disintegration or destruction due to weather conditions to which the sign may be exposed.

Another object of the invention is to provide a sign structure of simple construction, efficient in its operation and economical to manufacture.

A further object of the invention is to provide novel and efficient means for securing letters, numerals or other indicia to a suitable mounting or support.

A still further object of the invention is to improve devices of the character described in sundry details hereinafter referred to and particularly pointed out in the appended claim.

One embodiment of the present invention is shown for illustrative purposes in the accompanying drawing in which:

Fig. 1 is a perspective view of my improved sign embodying features of the present invention;

Fig. 2 is a fragmentary sectional view through a letter and portion of the backing member therefor illustrated in Fig. 1, and taken substantially as indicated by the line 2—2 thereof;

Fig. 3 is a face view of a modified form of support and a plurality of letters associated therewith; and

Fig. 4 is a sectional elevational view, taken substantially as indicated by the line 4—4 of Fig. 3.

The illustrative embodiment of the present invention, as shown in the drawing, comprises a plurality of letters or units, indicated generally by the numeral 5, and shown in Figs. 1 and 2 as adapted to be mounted on a backing member

6 extending beyond the edge portions of the letters 5 and in a suitable manner to provide various indications or other matter, each of the letters shown in the drawing, comprising a body indicated, as a whole, by the numeral 7, and formed, preferably, of transparent material such as glass or the like, and having, preferably, a roughened light-diffusing face portion 8 and a smooth rear side portion to which a metallic coating 9 such, for example, as silver or the like, is applied to provide a light-reflecting surface on the rear side of the body 7.

Over the coating 9 is a hard protecting material or coat 11 applied, preferably, in a pliable or plastic form and permitted to harden in a manner to resist weather conditions such as moisture, changes in temperature, or other atmospheric conditions to effectually protect the silver or reflecting surface from scratching during the manufacture as well as from the effects of weather conditions to which the sign may be subjected, and which otherwise might tend to tarnish or cause disintegration of the silver or other reflecting material, and eventually destroy the efficiency of the sign.

For securing the letter or other indicia to the backing member 6, a cementitious or other adhesive material 12, such, for example, as cement or the like may be applied to the protecting material or coat 11 and the letter as a whole applied to the backing member 6 as clearly illustrated in Fig. 2 for securing the letter to the backing member.

For protecting the edge portions of the letter against damage such as chipping or the like, and to provide further protection for the light-reflecting material 9, a cover strip 13, preferably, of L-shaped cross section is applied to the edge portions of the body material 7 in a manner to overlie the edge portions of the completed letter and a portion of the front side of the body material as clearly illustrated in Fig. 2, the cover strip 13 having an edge portion thereof abutting the face or front side of the backing member 6 and provided with sealing means 14 of suitable material such, for example, as solder or the like positioned adjacent the abutting portions of the cover strip 13 and backing member 6.

By reference to Figs. 1 and 2, it will be noted that the letters shown are all mounted directly on the backing strip 6, but to provide a sign of the character described wherein letters or other indicia may be interchangeably positioned with respect to each other, it will be noted by reference to Figs. 3 and 4 that the respective letters may

be positioned on individual backing members 6a extending beyond the edge portions of the letter, and the backing members 6a removably positioned in a suitable support indicated, as a whole, 5 by the numeral 15, having, preferably, an elongated channel 16 formed therein and provided with retaining portions 17 adjacent the opposite longitudinal side portions of the channel adapted to engage the outwardly extending portion of the 10 backing members 6a for retaining the letters against accidental displacement with respect to the support 15, and for retaining the letters against movement or displacement longitudinally of the channel, filler pieces or blocks 18 may be 15 positioned in the channel and secured to the support 15 by means of screws 19 as clearly illustrated in Fig. 3.

It will be observed from the foregoing description that the present invention provides a novel, 20 durable, and efficient sign construction of the light-reflecting type wherein the reflecting material is effectually protected at all times and wherein novel means are provided for securing the letters, numerals, symbols or other indicia to 25 a suitable backing member, and that the present invention also provides a device of simple construction which is economical to manufacture.

Obviously, the present invention is not limited to the precise construction and arrangement shown and described as the same may be variously modified without departing from the spirit and scope of the invention as set forth in the ap- 5 pended claim.

What I claim as new and desire to secure by Letters Patent is:

In a sign, the combination of a letter comprising a body of transparent material having a 10 smooth surface on its rear side and a light-diffusing surface on its front side, a metallic coating on said body having a light-reflecting surface adjacent the rear side thereof, a protecting coat of hardened plastic material on said metallic coating, a backing member extending beyond the edges of said transparent material, a cementsitious material adjacent said protecting coat for securing the letter to said member, a cover strip of substantially L-shaped cross section overlying the 20 edges and a portion of the front side of the transparent material, said cover strip having an edge portion abutting and secured to the front side of said backing member, and sealing means around said letter adjacent the abutting portions of said 25 strip and backing member.

EVERETT L. REGISTER.
